(57) **CLAIM**

We claim the ornamental design for an optical fiber cable with feedthrough, as shown and described.

DESCRIPTION

FIG. 1 is a first top plan view of an optical fiber cable with feedthrough, showing the new design;

FIG. 2 is a second top plan view thereof;

FIG. 3 is a right side elevational view thereof;

FIG. 4 is a left side elevational view thereof;

FIG. 5 is an enlarged view of the portion 5-5;

FIG. 6 is an enlarged perspective view thereof;

FIG. 7 is an enlarged right side view thereof; and,

FIG. 8 is an enlarged left side view thereof.

The dashed broken lines show portions of the optical fiber cable with feedthrough that form no part of the claimed design.
